UNITED STATES PATENT OFFICE.

FREDERICK C. HELLMUTH, OF BROOKLYN, NEW YORK, ASSIGNOR TO HIMSELF AND JOHN MUNZ, JR., OF SAME PLACE.

CARPET-FASTENER.

SPECIFICATION forming part of Letters Patent No. 314,671, dated March 31, 1885.

Application filed May 21, 1884. (No model.)

To all whom it may concern:

Be it known that I, FREDERICK C. HELLMUTH, of Brooklyn, (Green Point,) in the county of Kings and State of New York, have 5 invented certain new and useful Improvements in Fasteners for Mattings, of which the following is a specification.

The object of this invention is to furnish an improved fastening device for mattings, stair-carpets, &c., of such construction that the matting can be quickly and conveniently taken up at any time, cleaned, and relaid again, and also reversed, so as to be used on the other side.

15 In the accompanying drawings, Figure 1 represents a plan of a piece of matting secured to the floor by my improved fasteners. Fig. 2 is a top view of the floor-socket with the locking-piece partly in section. Fig. 3 is 20 a side view of the locking-piece; Fig. 4, a section through the fastener, and Fig. 5 a bottom of the fastener.

Similar letters of reference indicate corresponding parts.

25 A in the drawings represents a socket that is preferably made in disk shape and provided with an elongated slot, *a*, and a bottom rim, *b*. The socket *A* is countersunk into the floor, so that it is flush with the same, and secured by means of two or more screws, *d d*, which are passed through holes *d* of the socket *A*. A locking-piece, *B*, of double-T shape, is passed through a slit of the matting and a washer, *e*, interposed between each head *e* of the locking-piece *B* and the matting; but the washers may be dispensed with. The shank 35 of the locking-piece *B* is made of such a height as to correspond to the average thickness of the matting. The heads of the locking-piece *B* are provided with longitudinal nicks for turning the same by means of a screw-driver, pocket-knife, or other device.

When it is desired to lay the matting, the 45 sockets *A* are screwed down into recesses of the floor, and the locking-pieces *B* of the matting then connected to the sockets. This is accomplished by inserting the head *e* at the under side of the matting into the slot of the socket *A* and then turning the locking-piece 50 either by hand or by a screw-driver so that

it is placed across the slot of the socket, in which position it rigidly retains the matting on the floor. For detaching the same the locking-piece is turned back into line with the slot of the socket, and the matting then taken up for being cleaned. It is then relaid in the same manner, or after having been reversed so as to expose the other side to wear, in which case the opposite head of the locking-piece serves for locking the matting to the socket in 55 the same manner as before described.

The advantages of my improved fastener are that a neat and reliable connection of the matting with the floor are obtained, and the zinc strips which have been used heretofore to 60 strengthen the ends of the matting, and which are liable to split and break after the mat has been in use for some time, are dispensed with. By fastening the corners of the matting, they cannot curl up and cause persons to fall.

The fastener is cheap, strong, and durable, and can be readily detached from one matting after the same has been worn out and attached to a new matting.

Having thus described my invention, I 75 claim as new and desire to secure by Letters Patent—

1. In a matting-fastener, the combination of a plate or socket piece adapted for attachment to the floor and provided with an elongated slot, and a double-headed locking-piece whereof one head is adapted to pass through the matting, the opposite elongated head being adapted to pass through said slot and lock under said socket-piece, substantially as described.

2. The combination of a slotted socket having a raised rim at the under side, means to lock the socket flush with the floor, a double-T-shaped locking-piece passed through the 90 matting, the heads of said locking-piece having longitudinal nicks, substantially as set forth.

In testimony that I claim the foregoing as my invention I have signed my name in presence 95 of two subscribing witnesses.

FREDK. C. HELLMUTH.
